HERMETIC SEAL

Victor J. Francis, North Wembley, and Eric Kettlewell, Wembley Park, England, assignors to General Electric Company, a corporation of New York

Application January 27, 1941, Serial No. 376,228
In Great Britain January 2, 1940

2 Claims. (Cl. 176—126)

This invention relates to high pressure vapor electric discharge devices with envelopes of quartz or like material of the type in which at least one leading-in electrical conductor is introduced into the envelope by means of an hermetic strip seal and in which, during full operation, the pressure exceeds 5 atm. Material like quartz means any vitreous, highly siliceous material having a coefficient of expansion not greater than 1.5×10^{-6} per °C. measured under conditions such that the coefficient of expansion of quartz is 0.55×10^{-6} per °C. In what follows the word quartz will be used for brevity to mean "quartz or like material."

In the making of a strip seal, a quartz tube is usually collapsed onto both the strip itself and a stouter conductor to which the end of the strip is attached. Since the quartz shrinks away from the stouter conductor when the seal cools, an annulus is left between the quartz and the conductor terminated by a sharp angle. Again when, as is usual, the device is made by sealing an already prepared strip seal into an aperture in the quartz envelope, an annulus is apt to be left between the quartz of the seal and the quartz of the envelope also terminated by a sharp angle. We have found that the presence of these sharp angles leads to mechanical weakness of the envelope which is apt to burst when a high vapor pressure is developed within it during operation of the device. The object of the invention is to avoid this difficulty and to increase the mechanical strength of such envelopes.

No method is known by which the presence of the sharp angle between the stout conductor and the quartz can be avoided. But we have discovered that the weakness of the envelope due to it can be greatly reduced by causing the gap terminating in the sharp angle to lie within the envelope, so that the pressure within the gap is opposed by pressure outside it.

The invention will be readily understood by an inspection of the accompanying drawing and a perusal of the following detailed description thereof.

In the drawing Fig. 1 is a front elevational, partly sectional view of the strip seal and the neighboring part of the quartz envelope showing the relative position of these elements with respect to each other in prior structures; Fig. 2 is a similar view of the seal and the envelope during manufacture while the adjoining parts of these elements are still soft and plastic; Fig. 3 is a similar view of a structure embodying the invention; and Fig. 4 is a similar view of a discharge device of the high pressure type embody-

ing the improvement. Like numbers denote like parts in all the figures.

In the manufacture of the device a quartz tube is collapsed onto an electrical conductor comprising a thin, foil-like strip 10 of molybdenum, for example, to which a stouter conductor 4 is fastened as by welding. The conductor 4 consists of a wire or strip of refractory metal, such as molybdenum or tungsten, and is of such thickness that the quartz does not make an hermetic joint therewith as it does with the strip 10. The seal element or plug thus formed has a gap 5 between the stout conductor 4 and the quartz element 1. The gap 5 is of appreciable depth and terminates in a sharp angle as shown in Fig. 1 of the drawing.

In prior structures the seal element has been fused into the tubular extension 2 of the envelope 3 of the discharge device as shown in Fig. 1 of the drawing, that is with the part of the quartz 1 surrounding the gap 5 outside the envelope 3 and in the extension 2. The pressure of the gaseous atmosphere in the envelope 3 is usually less than atmospheric pressure when the envelope 3 is at room temperature and is 5 atmospheres and higher when the device is operating. During operation of the device the high pressure exerts force of considerable magnitude in the gap 5 tending to burst the seal as indicated by the arrows in Fig. 1. Since the gap terminates in a sharp angle, as pointed out above, it is a point of mechanical weakness of the device. In accordance with the present invention the part of the quartz element 1 surrounding the gap 5 is mounted within the space defined by the envelope 3 where the force tending to burst the seal is opposed by force tending to compress it, as indicated by the arrows in Fig. 3.

The sharp angle between the quartz element 1 and the envelope 3 characteristic of prior devices is shown at 7 in Fig. 1 of the drawing. This sharp angle 7 is a weak part of the envelope 3 of the device which is strengthened by moving the quartz element 1 further into the envelope 3 after these parts have been joined by fusion and while the quartz is still plastic. The sharp angle 7 is thus changed to the much more gradual transition part 8, as shown in Fig. 3, to increase the mechanical strength of the envelope 3.

The quartz element 1 is pushed into the envelope 3 an effective distance without decreasing the thickness of the quartz at any part when an annular bulge 9 is provided on said element 1 before it is fused to the tube 2. The bulge 9 is

utilized to support the element 1, which acts as a plug for the envelope 3, in proper position in the tube 2 prior to the fusion of these elements, when desired. Fig. 2 shows the preferred position of the bulge 8 on the element 1 with respect to the angular opening about the conductor 4. The completed seal is shown in Fig. 3.

Fig. 4 illustrates a complete discharge lamp having seals embodying the present invention. Electrodes 11 are mounted on conductors 4 and are separated a few millimeters from each other in the substantially spherical envelope 3. The envelope 3 has therein a starting gas, such as neon, at a pressure of about 5 mm. and a quantity 12 of vaporizable material, such as mercury, sufficient to produce a vapor pressure of at least about 5 atmospheres during the operation of the lamp. The electrodes 11 are hollow, pointed, perforated metal shells, such as tungsten shells, containing material of high electron emissivity characteristics, such as barium or strontium, or mixtures of such materials. As shown in Fig. 4 of the drawing the hermetic fused joint between the quartz element 1 of the plug and the metal strip 10 terminates in the space defined by the envelope 3 and the gap between the quartz element 1 and the conductor 4 is within said space. The lamp described above is a long-lived compact, mechanically strong, highly efficient light source of high intrinsic brilliancy.

What we claim as new and desire to secure by Letters Patent of the United States is:

1. An envelope for an electric discharge device of the high pressure type, said envelope having a perforated part consisting of a vitreous material

which has the characteristics of quartz, a plug of similar vitreous material fused into and hermetically sealing said envelope part, said plug extending from the interior to the exterior of said envelope, and an electrical conductor extending through said plug, said conductor comprising a thin, foil-like strip of metal hermetically fused into and terminating in said plug at an appreciable distance from the end of said plug in said envelope and a metal wire connected to said strip in said plug and extending into said envelope, the dimensions of said wire being such that it is incapable of making a fused hermetic joint with said plug, the part of said plug surrounding said wire being in said envelope to increase the mechanical strength of said envelope.

2. A quartz-to-metal seal for a vitreous envelope comprising a cylindrical member of quartz, an electrical conductor sealed through said cylindrical member, said conductor comprising a thin, foil-like strip of metal hermetically fused into and terminating within said cylindrical member and a metal body connected to said strip in said cylindrical member and extending beyond said cylindrical member, said metal body being incapable of making a hermetic joint with said cylindrical member, said cylindrical member having an annular protuberance thereon between the ends of said metal strip for supporting said seal in said envelope and providing material for the formation of a rounded surface between said envelope and said cylindrical member when these elements are combined by fusion.
